ABSTRACT

A pair of heat pipes are placed within the interior of a pipe pile which has been grouted within an earth bore-hole. A predetermined amount of water is metered into the bottom of the interior of the pipe pile and then dry sand is added to the water. Various means are disclosed for vibrating the sand and water mixture including the vibration of the heat pipes and/or the vibration of the pipe pile.

FIG. 1

FIG. 3

FIG. 2

METHOD OF PACKING HEAT PIPES WITHIN A PIPE PILE INVOLVING THE VIBRATION OF THE PACKING MATERIAL

RELATED APPLICATION

This application relates to my co-pending U.S. Pat. application Ser. No. 396,934, for "METHOD OF GROUTING A PILE IN A HOLE INVOLVING THE VIBRATION OF THE GROUTING MATERIAL", filed on Sept. 13, 1973 and now U.S. Pat. No. 3,839,874.

BACKGROUND OF THE INVENTION

This invention relates generally to the packing of one or more heat pipes within the interior of a pipe pile, and particularly relates to the packing of such heat pipes within the interior of a pipe pile while vibrating the packing material.

As described in the aforementioned related United States patent application, it has been proposed to build various pipelines across Alaska which will have piles grouted in place within holes using a mixture of sand and water in the annulus external to the pipe pile. It has also been proposed that a sand and water mixture be used to pack the heat pipes within the interior of the pipe pile to provide heat pipe stabilization of the pipe pile. This general area has been discussed in U.S. Pat. No. 3,788,389, for "PERMAFROST STRUCTURAL SUPPORT WITH HEAT PIPE STABILIZATION" which issued on Jan. 29, 1974. It should be appreciated, moreover, that much of the construction work on these pipelines will be done under extremely frigid temperature conditions, for example, -60°F. These extreme conditions create problems with icing of the water being used and bridging within the interior of the pipe pile when pouring a sand and water mixture therein. Furthermore, it has been discovered that even while vibrating the mixture, the mixture will sometimes not be compacted around the heat pipe to such a degree as to create a satisfactory packing of the heat pipe within the interior of the pipe pile.

It is therefore the primary object of the present invention to provide a new and improved method of packing a heat pipe within the interior of a pipe pile;

It is also an object of the invention to provide a new and improved method of packing one or more heat pipes within the interior of a pipe pile which eliminates many of the problems encountered while using water in subfreezing temperature conditions; and

It is yet another object of the present invention to provide new and improved methods for vibrating the packing material used in packing a heat pipe within the interior of a pipe pile.

The objects of the invention are accomplished, in general, by a method of packing one or more heat pipes within the interior of a pipe pile which involves the placement of such heat pipes within the interior of the pipe pile, the addition of water to such interior and then the addition of sand to the interior and the vibration of the packing material which causes the sand and water mixture to be fluidized along the length of the interior of the pipe pile.

These and other objects, features and advantages of the present invention will be more readily understood from a reading of the following detailed specification and drawing, in which:

FIG. 1 is an elevated view, partly in cross section, of a pipe pile which has been grouted within an earth borehole in accordance with the methods disclosed in my aforementioned United States patent application;

5 FIG. 2 is an elevated view, partly in cross section, which illustrates apparatus for vibrating the heat pipes and for adding water and sand to the interior of the pipe pile in accordance with the present invention; and

10 FIG. 3 illustrates, in elevation and partly in cross section, the heat pipes which have been packed within the interior of the pipe pile in accordance with the methods according to the present invention.

Referring now to the drawing in more detail, especially to FIG. 1, there is illustrated a hole 10 in the 15 earth 11 which may be either a conventional earth formation, or may be comprised of permafrost in the more frigid zones of the earth, for example, in Alaska. A steel pipe pile 12 is grouted within the hole 10 in accordance with the principles of my aforementioned related 20 United States patent application. The pipe pile 12 is grouted within the hole 10 by a compacted sand and water mixture 13. As is explained in the aforementioned related application, the pipe pile 12 may or may not have a bottom end plug at its lower extremity.

25 Referring now to FIG. 2, a pair of heat pipes 20 and 21 separated by one or more separators 22 along their length are placed within the interior of the pipe pile 12. It should be appreciated that the heat pipes themselves 30 are conventional and may take several forms, for example, as illustrated and described, in U.S. Pat. No. 3,788,389. Alternatively, heat pipes such as Model 35 1333H available from the Hughes Electron Dynamics Division, 3100 West Lomita Blvd., Torrance, California 90509 can be used. A vibrator 23 is attached to the top portion of the heat pipes 20 and 21 to vibrate such heat pipes along their length. A source of water 24 and a source of sand 25 are provided for placing water and sand into the interior of the pipe pile 12.

40 In practicing the method in accordance with the apparatus illustrated in FIG. 2, the heat pipes 20 and 21 are placed inside the interior of the pipe pile 12 and water 26 is then metered into the interior of the pipe pile 12 from the water source 24 in a predetermined 45 amount which is determined by the area of the interior of the pipe pile along the entire length of the pipe pile 12 and by the amount of water as is desired in the final sand and water mixture. By way of example, a recommended packing mixture should have a water content 50 of 8% to 15% by dry weight. The 15% water content has been found to be highly desirable in that the mixture is highly fluidized during at least a portion of the method according to the present invention.

55 After the water 26 is added to the interior of the pipe pile 12 and is residing in the bottom of the pipe pile, the dry sand is added to the interior of the pipe pile 12 from the sand source 25 and the vibrator 23 is used to vibrate the heat pipes 20 and 21 which in turn causes the sand and water mixture to vibrate. Because of the important feature of adding the water to the interior of the pipe pile first, no air bubbles are found within the sand and water mixture as would be the case if either the sand was added first or if the sand and water slurry 60 was mixed prior to adding the mixture to the interior of the pipe pile. By placing the water in the interior first, and by vibrating the sand and water mixture, it has been found that there is an excellent adherence of the 65

sand and water mixture to the interior of the pipe pile and to the heat pipes themselves.

Referring now to FIG. 3, the pipe pile 12 is illustrated as being grouted in place by the grouting material 13 and the heat pipes 20 and 21 are illustrated as being packed within the interior of the pipe pile 12 by the packed sand and water mixture 27 as discussed above with respect to FIG. 2.

Although not illustrated, a protective casing can be used along the length of the hole between the grouting material 13 and the earth formation 11 as desired.

Thus it should be appreciated that there have been described herein the preferred embodiments of the present invention wherein various methods are described relating to the packing of one or more heat pipes within the interior of a pipe pile within an earth borehole. Although the preferred embodiments contemplate the use of sand, the word "sand" is to be construed in a generic sense and it is contemplated that various sand-like materials or minerals can be used in place of the conventional silica sand. Furthermore, it should be appreciated that even though the preferred embodiments contemplate the sand/water mixture be vibrated commencing with the addition of the sand to the water, those skilled in the art will recognize that a given amount of sand can be added to the water before commencing the vibration step. Likewise, after the vibration has ceased, dry sand can, if desired, be added to the very top of the interior of the pipe pile 12. Likewise, although the preferred embodiment contemplates that the heat pipes be placed within the interior of the pipe pile and then the water added to such interior, those skilled in the art will recognize that the water can be added to the interior of the pipe pile first and then the heat pipes placed within the pipe pile without departing from the spirit of the invention. Likewise, those skilled in the art will recognize that, on occasion, there may already be some amount of water within the interior of the pipe pile for various reasons and that a smaller amount of water, perhaps zero, need be added to the interior of the pipe pile before adding sand. Furthermore, the sand and water mixture can be vibrated by other means, for example, by vibrating the pipe pile itself or by inserting a vibrating rod into the sand and water mixture.

It should also be appreciated that while the preferred embodiment contemplates that the pipe pile is first grouted in place within an earth borehole in accordance with the principles of my aforementioned related United States patent application, it should be appreciated that both the grouting of the pipe pile within the earth borehole and the packing of the heat pipes within the interior of the pipe pile can be accomplished in a single step. Thus, by adding water to the annulus exterior to the pipe pile and also to the interior of the pipe pile having the heat pipes therein and by shortly thereafter adding sand to the annulus exterior to the pipe pile and to the interior of the pipe pile while vibrating the pipe pile, the pipe pile is thus grouted within the earth borehole simultaneously with the packing of the heat pipes within the interior of the pipe pile.

The embodiments of the invention in which an exclusive property or privilege is claimed are defined as follows:

1. A method of packing at least one heat pipe within a pipe pile, comprising:

placing at least one heat pipe within the interior of said pipe pile;

metering a predetermined amount of water into the interior of said pipe pile;

placing sand in said water to form a sand and water mixture after said water is in place in the bottom of said pipe pile; and

vibrating said sand and water mixture, said mixture having enough water to remain fluidized during said vibration.

2. The method according to claim 1 wherein said at least one heat pipe comprises a pair of heat pipes.

3. A method of packing at least one heat pipe within a pipe pile, comprising:

placing at least one heat pipe within the interior of said pipe pile;

adding water to the interior of said pipe pile;

adding sand to said water to form a sand and water mixture within the interior of said pipe pile after said water is in place in the bottom of said pipe pile; and

vibrating said sand and water mixture, said mixture having enough water to remain fluidized during said vibration.

4. A method of packing at least one heat pipe within the interior of a pipe pile, comprising:

placing at least one heat pipe within the interior of a pipe pile;

adding water to the interior of said pipe pile;

adding sand to said water to form a sand and water mixture within the interior of said pipe pile after said water is in place in the bottom of said pipe pile; and

vibrating said sand and water mixture as said sand is added, said mixture having enough water to remain fluidized during said vibration.

5. A method of packing at least one heat pipe within the interior of a pipe pile, comprising:

placing at least one heat pipe within the interior of a pipe pile;

adding water to the interior of said pipe pile;

adding sand to said water to form a sand and water mixture within the interior of said pipe pile after said water is in place in the bottom of said pipe pile; and

vibrating said at least one heat pipe while said sand is being added to said water, said mixture having enough water to remain fluidized during said vibration.

6. A method of packing at least one heat pipe within the interior of a pipe pile, comprising:

placing a heat pipe within the interior of a pipe pile;

adding water to the interior of said pipe pile;

adding sand to said water to form a sand and water mixture within the interior of said pipe pile after said water is in place in the bottom of said pipe pile; and

vibrating said sand and water mixture; and ceasing to vibrate said sand and water mixture while said mixture is still fluidized.

7. A method of packing at least one heat pipe within the interior of a pipe pile, comprising:

placing at least one heat pipe within the interior of a pipe pile;

adding water to the interior of said pipe pile;

adding sand to said water to form a sand and water mixture within the interior of said pipe pile after said water is in place in the bottom of said pipe pile; and

vibrating said at least one heat pipe while said sand is being added to said water; and ceasing to vibrate said at least one heat pipe short of adding sand in such an amount that said sand and water mixture would no longer be fluidized.
